Filed Nov. 29, 1966, Ser. No. 4,848

Term of patent 14 years

(Cl. D57—1)

FIG. 1

FIG. 2

FIG. 3

FIG. 4

FIG. 1 is a front view of a pair of eyeglasses showing my new design;

FIG. 2 is a side view of said eyeglasses taken from the right side thereof as viewed in FIG. 1;

FIG. 3 is a top view thereof; and

FIG. 4 is an enlarged sectional view taken along the line 4—4 in FIG. 1 and looking in the direction of the arrows.

The temple portion is shown broken away in FIG. 3 for convenience of illustration.

The side not shown has substantially the same appearance as the side shown.

My design for the pair of eyeglasses disclosed is characterized by the bead-like configuration of the marginal edge encompassing the inside of the lens holding portions, in association with the remaining portions of the said eyeglasses as shown.

I claim:

The ornamental design for a pair of eyeglasses, substantially as shown and described.
